JOHN MARSHALL, OF GREENWICH, ASSIGNOR TO JOHN CHRISTOPHER REES WEGUELIN, OF LONDON, ENGLAND.

Letters Patent No. 85,179, dated December 22, 1868; patented in England, February 25, 1867.

IMPROVEMENT IN SAFETY-GAUGES FOR BOILERS.

The Schedule referred to in these Letters Patent and making part of the same

To all to whom these presents shall come:

Be it known that I, JOHN MARSHALL, of Greenwich, in the county of Kent, England, civil and mechanical engineer, have invented an "Improved Fluid-Safety Gauge;" and that the following is a full, clear, and exact description of the principle or character which distinguishes it from all other things before known, and of the usual manner of making, modifying, and using the same.

My improved fluid-safety gauge (which I call a self-acting fluid-safety gauge) is applicable to steam-boilers and other vessels where fluids are employed either above or below the atmospheric pressure, by means of which, in the event of the gauge-glass or indicating-receptacle breaking or being broken, no escape of steam, fluid, or air shall take place, beyond that contained within the said glass or indicating-receptacle itself.

My invention is also applicable to ordinary fluid-gauges, and to vacuum-vessels and condensers of marine and other engines.

The accompanying drawing shows a safety-gauge fitted with a spherical valve acting horizontally, as an illustration of the application of my invention, it being the most simple form of construction; but I do not confine myself to this particular form of valve, as, under different circumstances, I can use another form of valve, such as the differential throttle, butterfly, or spindle-valve, and suit the action of the valve, whether in a vertical, horizontal, or inclined position, to the form of valve used, and I suit the position, whether inside or outside the cock, to the action of the valve.

Figure 1 is a side elevation of my improved fluid-safety gauge.

Figures 2, 3, 4, and 5 are vertical sections through the passage-way of the cock and plug, showing the different positions and actions of the plug and spherical valve, the pressure being in the direction indicated by the arrows.

In the construction of this fluid-safety gauge, or the alteration of existing ones, I take the plugs A, figs. 2, 3, &c., and chamber them out, so as to form a conical seating at one end, as shown at B, fig. 2, and insert a metallic or other ball or pea, E, of sufficient diameter to rest upon the seating B.

At the other end of the chambered steam and fluid-ways, I insert a piece of metal, C, bored out through its centre, to the same diameter as the original steam and fluid-ways. A portion of its external diameter, next the "pea," is turned down to about half its thickness, and through this reduced part apertures are made, from the outside into the centre hole, forming a perforated seat. The plug being now complete, is fitted back into its place.

I also, for the purpose of cleaning the ball and seatings, with the pressure or vacuum in action, bore a hole

in the under side of the shell, of a diameter larger than the piece C, and fit into the same a screw-plug, D.

The action of the safety-gauge is as follows:

Figure 2 shows the ball in its normal position, or when, the glass tube being perfect, the pressure is equal on both sides of the ball.

Figure 3 shows the ball (from the glass being broken and the balance of pressure destroyed) driven firmly against the seating B, thereby preventing any escape of steam, air, or fluid.

Figure 4 shows the ball in the position for blowing off, the handle of the cock having been reversed, or turned upside down, whereby the pressure drives the ball against the perforated seat C, and the steam, air, or fluid escapes round the ball and through the perforations, as indicated by the arrows.

Figure 5 shows the method of taking out the seating and valve without taking out the plug or destroying the pressure or vacuum. For this purpose, I turn the handle of the cock a quarter round, so as to bring the perforated seating C opposite the screw-plug D. I unscrew the plug D, and take out the seating C (by means of a key inserted for that purpose) and the ball-valve E. I then clean and replace them, as well as the plug D, and the gauge is again ready for use.

Figure 6 is a side elevation, and

Figure 7, a side centre section of a gauge for vacuum-vessels or condensers of engines constructed on the safety-principle.

The construction of the cock is the same as for the pressure-gauge hereinbefore described, except that in use the handle is turned up for safety, as shown in fig. 6, instead of hanging down; and for the purpose of condensers or other vacuum-vessels, where the fluid is below of invisible from the working-platform, I extend the tube to any convenient height, having within a float resting upon the surface of the liquid, and a light rod or counter-balance, with a pointer, indicating at some convenient height.

What I claim as my invention, and desire to secure by Letters Patent, is—

1. The ball-valve E, or its equivalent, in combination with the conical-seated plug A and the perforated seating C, the whole being constructed and arranged substantially as herein described.

2. The screw-plug D, in combination with the valve E, the perforated seating C, and the conical-seated plug A, the whole being constructed and arranged substantially as herein set forth.

In testimony whereof, I, the said JOHN MARSHALL, have hereto set my hand and affixed my seal, this 23th day of August, A. D. 1868.

Witnesses: JOHN MARSHALL. [L. S.]
